(57) **CLAIM**

We claim the ornamental design for a bullhorn cup, as shown and described.

DESCRIPTION

FIG. 1 is an exploded top front perspective view of a bullhorn cup showing our new design with the handles in extended position;

FIG. 2 is an exploded front elevational view thereof with the handles in stowed position;

FIG. 3 is an exploded front elevational view thereof with the handles in extended position;

FIG. 4 is an exploded rear elevational view thereof;

FIG. 5 is a left side elevational view thereof with the handles in stowed position;

FIG. 6 is a left side elevational view thereof with the handles in extended position;

FIG. 7 is a right side elevational view thereof with the handles in stowed position;

FIG. 8 is a right side elevational view thereof with the handles in extended position;

FIG. 9 is a top plan view thereof with the handles in extended position; and,

FIG. 10 is a bottom plan view thereof with the handles in extended position.
